ELECTRIC DISCHARGE VESSEL

Rudolf Scharfnagel, Stuttgart, and Felix Herriger, Berlin, Germany, assignors to C. Lorenz Aktiengesellschaft, Berlin-Tempelhof, Germany, a company

Application April 3, 1940, Serial No. 327,646
In Germany March 30, 1939

2 Claims. (Cl. 250—27.5)

This invention relates to electric discharge vessels of the kind having a glass seal fitted to the bulb which is preferably made of metal in order to serve as anode in well known manner.

It has been proposed to increase the thermal loading capacity of these devices by raising the thermal inertia effective in the neighbourhood of the glass seal. The means best adapted for this purpose is a heat accumulating body arranged in close proximity to the glass seal. Such body may be of a suitable metal. Metal, however, although very suitable in this regard, increases the detrimental capacities and thus impairs the electric properties of the discharge vessels.

According to the invention the heat accumulating body is constituted by the insulating carrier of the electrode system. This carrier preferably consists of ceramic material. According to a further feature of the invention such ceramic carrier is made of sintered corundum.

In the accompanying drawing Fig. 1 is a somewhat diagrammatic sectional view showing one embodiment of the invention; Fig. 2 is a partly broken away and sectionalized view of this embodiment; and Fig. 3 represents a section taken in the plane of line A—A of Fig. 1.

The discharge vessel here illustrated by way of example has a metallic bulb 1 which is conically enlarged at 2. The electrode system E is supported by leads 3 which are carried by means of a block 4 of a dense ceramic material. This block is pressed into the bulb so as to snugly contact with the wall thereof. To the outer end face of block 4 a disc 5 is fixed by means of vitreous material that forms a glass disc 7 and reaches through perforations 6 of the disc 5. Disc 5 is of a porous ceramic material.

The disc 5 may be fixed to block 4 by a sintering process to which a separate glazing frit or some other binding agent of low vapor pressure is subjected during the process of producing the glass disc 7.

The disc 5, however, need not at all be united with block 4. The procedure in this case may be as follows: In the first place, the assembly 3, 5, 7 is manufactured. Then the block 4 is inserted over the leads 3, whereupon the electrode system E is mounted on the leads. Finally, the supporting assembly 3, 4, 5, 7 for the system E is sealed into the bulb 1.

Alternatively, the disc 5 may be omitted and the block 4 may be in its turn porous. In this case block 4 may also be provided with longitudinal bores or with recesses formed in close

adjacency in the outer end face thereof. In this way vitreous material applied to this end face will enter such grooves or recesses when melted down, being transformed thereby into a glass disc equivalent to the disc 7 shown in the drawing.

The block 4 is a solid body which is easy to manufacture. Owing to the fact that this block intimately contacts with the bulb 1 the heat from this bulb is directly transferred to it. The heat conductivity of the ceramic material of which the block is made is such that the heat received from bulb 1 is quite uniformly distributed in the block, which therefore in its turn and with the aid of disc 5 acts to transfer the heat to the glass disc 7 uniformly to all parts thereof.

Block 4 may consist of magnesium silicate, such as the materials known under the names "Frequenta" or "Calite." Preferably, however, sintered corundum is suitable for this purpose. In fact, the heat conductivity of this material is ten times that of the two other said materials, the heat received by block 4 thus being distributed most uniformly over the glass disc 7 so as to prevent strains arising therein. In this way the glass disc 7 will be able to stand temperatures of 600° to 700° C. during long periods of operation.

In distinction from prior arrangements having metal arranged as a heat accumulating means, in the case of the novel device the inherent dielectric losses and capacity conditions are not affected to disadvantage since the heat accumulating means 4, 5 is of insulating material so as not to diminish in electric relation the distance between the leads 3 and the metal wall of bulb 1.

What is claimed is:

1. A discharge vessel comprising a metal bulb having an opening therein, heat accumulating means blocking said opening comprising a carrier body of dense ceramic material snugly fitted to the wall of said bulb and a disc of porous ceramic material, means for mounting an electrode system on said body, and a glass seal covering said means and sealed to said bulb, said disc being located between said body and said seal.

2. A discharge vessel according to claim 1 wherein said disc is fixed to said body by a binding agent of low vapor pressure, said agent being sintered to said body and said disc.
